UNITED STATES PATENT OFFICE.

GLENN H. CURTISS, OF BUFFALO, NEW YORK, ASSIGNOR TO CURTISS AEROPLANE & MOTOR CORPORATION, A CORPORATION OF NEW YORK.

FLYING-BOAT HULL.

1,223,319.

Specification of Letters Patent. Patented Apr. 17, 1917.

Application filed December 6, 1915. Serial No. 65,372.

To all whom it may concern:

Be it known that I, GLENN H. CURTISS, a citizen of the United States, residing at Buffalo, in the county of Erie and State of New York, have invented certain new and useful Improvements in Flying-Boat Hulls, of which the following is a specification.

My invention relates to boat hulls of a character designed for service in connection with that type of hydroaeroplane known as the flying boat. This type is predicated upon the provision of a vessel in itself capable of water travel and further equipped with aerial supporting surfaces for traveling through the air. The hull construction contemplated by this invention is, moreover, generally applicable to hydroplanes of any character, even if not designed for flying, while interior arrangements also contemplated can be readily employed in aeroplanes adapted to rise from and alight upon the land only.

In general, it is the object of my invention to provide a flying boat hull of increased carrying capacity, such hull being equipped with an elongated cockpit which extends both fore and aft of the supporting surfaces intermediately secured to the hull. This cockpit is so subdivided as to provide a pilot seat in tandem with, and in the rear of, the usual forward seats for the passengers. Between these compartments there is interposed a central storage space for such supplies as large quantities of motor fuel, where the occupants of any seat may have ready access thereto.

More specifically, the elongated cockpit which is formed in the new hull of this invention is subdivided into a plurality of separate compartments through the medium of water-tight bulkheads, the center compartment being designed as a storage space for both bulky and weighty materials and being properly placed over the hydroplaning step of the hull bottom, which forms a natural reinforcement to the hull at this point where the greatest weight is to be supported.

A further and correlated object of the foregoing is to arrange a wing panel having its beams built directly into the hull and extending transversely therethrough at the points where the water-tight bulkheads are provided for the subdivision of the main cockpit into the storage and seating compartments, this wing panel being thus so

disposed with the central weight-carrying storage space, as to define an approximately vertical alinement of the center of lift and the center of gravity.

It is a still further object to brace each of the wing beams thus transversely projected through the hull, fore and aft into a pair of adjacent compartments, in order that the entire structure may be made to form an efficiently unified whole.

It is an object of generic importance to provide a boat hull characterized by a hydroplaning bottom terminating in a rearwardly faced step and with a flat top which is coextensive with the step and rearwardly therebeyond, and to provide a tail portion having its top and bottom similarly forming converging angles from the corresponding parts of the main hull body, and having its sides finishing off lateral streamlines incurred by the sides of the said main hull body.

The above and additional objects, to be hereinafter more specifically treated, are accomplished by such means as are illustrated in the drawings, described in the following specification and then more clearly pointed out in the claims, which are appended hereto and form a part of this application.

With reference to the drawings, in which there is illustrated one embodiment of the invention, and throughout the several views of which like characters of reference designate similar parts,

Figure 1 is a side elevation of the boat hull before the erection thereon or attachment thereto of any of the structure fitting it for flight;

Fig. 2 is a plan view of the same subject matter;

Fig. 3 is a front end elevation of the hull;

Fig. 4 is a half plan of the forward portion of the body;

Fig. 5 is a half longitudinal section;

Fig. 6 is a half plan of the rearward portion of the hull, in continuation of Fig. 4;

Fig. 7 is a longitudinal section through the same hull portion in continuation of Fig. 5, and

Fig. 8 is a half transverse section taken on an appropriate plane forward of the wing structure of the hull.

In its general aspects, the boat hull provided by my present invention follows many of the lines of former types of flying boats

evolved by me. One great point of distinction, however, is to be particularly noted, and that distinction resides in the flattened hull top which extends horizontally rearward from the nose of the boat, in a manner coextensive with the hydroplaning bottom which continues rearwardly through the ninety degree curve of lessening angle to a termination in the transverse step. Extending rearwardly at an upper angle from the step and at a downward angle from the horizontal hull deck are the top and bottom portions of the tail, commonly terminating in the stern post.

15 The comfort of the occupants both with regard to their own disposal and with respect to the storage of the necessary supplies for the boat, has been made a major consideration in my invention. A single main cockpit of elongated formation is provided in the horizontal hull deck from the nose pontoon forward of the wing structure to a point some distance aft thereof. This main cockpit is subdivided by the bulkheads respectively associated with separate wing beams into a fore cockpit for passengers, an aft cockpit for the pilots, and a large central cockpit admirably adapted for storing purposes. Large supplies of such a necessary nature as fluid fuel may be carried in the storage cockpit, so that the cruising radius of the flying boat may be greatly increased, and the operators thereof be rendered less dependent upon supply stations. Moreover, the great weight of the necessary supplies which will be required in any extended cruise is taken up by the boat at its strongest portion, *i. e.*, that portion reinforced by the heavy planing step and its skeg, and by the trussing structure of the wing beam braces.

Having set forth in the foregoing a brief outline of the general characteristics of my new type of flying boat hull, together with particulars as to the improvements contemplated by my invention of this date, a more detailed exposition will be undertaken, and in the order indicated. The hull is built up in the essential streamline manner, having a comparative blunt nose 10 from which the sides 11 of the hull have a rearwardly elongated taper to the stern post 12. Flaring away from the blunt prow of the boat is the V-shaped planing bottom 13, such bottom being curved in the length of the boat from the nose 10 to merge into a rearwardly and downwardly inclined plane which terminates in the step 14. The deck 15 of the boat is flattened from the nose rearwardly to a point aft the step 14, being nearly parallel with the hull bottom and like the bottom, is rearwardly prolonged and terminated by the diminishing streamline tail. The hull is thus streamline in plan (Fig. 2) although the forward portion of

the elevational streamline is thus interrupted by the deck. Extending longitudinally from nose to planing step is the keel 16 upon which is laid the planking 17 of the V-shaped hydroplaning bottom of the fore-hull. Rearward of the step 14, a continuing keel 18 connects with the stern post and supports the rectangular bottom planking 19 of the tail.

The keel 16 has erected thereon the built and solid floors 20 and 21 in order to properly carry the bottom planking 17, while at the same time serving to support the interior flooring 22 of the boat. This method of construction terminates at the step 14, although the keel is continued therebeyond by the skeg 23 bracing such step, and the tail keel 18 to the stern post 12. Determining the cross-sectional or beam outlines of the boat are the hull frames 24 connecting to abutting floors by the heel plates 25 and interconnected to each other by the seam strips 26 upon which the outer skin of the sides 11 is laid.

Beyond these sides 11 the planking composing the hydroplaning bottom is extended laterally for the integral formation of fins 27 which provide auxiliary planing surfaces in conjunction with the mentioned bottom. Cap-strips 20' underlie the floors 20 to extend laterally beyond the sides or chines of the hull and afford, collectively, a base for that portion of the planking 17 constituting the fin bottoms. This construction is particularly advantageous in that the full hydroplaning area is constructed as a unit and without a break in its continuity laterally of the keel 16. These fins curve rearwardly out from the nose 10 in a streamline manner, in plan, which is terminated by the step 14. The upper surface of these fins connects back from the outer edges to the sides 11, in a manner which is essentially streamline in elevation. To these fins are braced the projecting wing structures, as will be later set forth.

Bilge boards 28 extend throughout the central length of the boat while chine stringers 29 are interposed between the extremities of the floors 20 and 21 and the lower edge of the hull walls 11, such stringers having the bottom planking 17 also fastened thereto. The gunwale stringers 30 reinforce the hull frames 24 within the cockpit 31 provided in the central portion of the boat. A combing 31^a serves to edge the cockpit, the fore and aft portions of which have erected therein the seat frames 32 and 33, the cockpit being subdivided in a manner to be later detailed.

Turning now to the description of the built-in wing structure which includes the construction of stub-wings at the time of building the boat hull in order that the supporting surfaces of the flying boat will

be afforded desirable points of attachment, the numerals 34 and 35 are employed to designate the forward and rear stub-wing beams respectively. The forward wing beam 34 is erected transversely of the boat and the cockpit 31, resting upon the gunwale stringers 30, and has associated therewith the compression braces 36 of the hull proper, such beam projecting laterally from the sides of the boat a sufficient distance to allow a desirable width to the wing surface 37 which is built thereon. The rear wing beam 35 projects through the hull below the gunwale stringers owing to the curvature or camber of the wing 37, but is similarly associated with the hull braces 38.

Standards or struts 39 are incorporated into each side 11 of the hull for the support of each end of the wing beams at their point of intersection with such sides. The bracing means for these wing spars form an important particular of this invention, and include a pair of interior braces 39 and 40 which act as diagonals between respective wing beams and the extremities of the planing step 14. Reaction braces 41 and 42 complete the trussing of these beams, all of which truss bracing or supporting means for the beams within the hull is particularly identified with the latter so that the achieved structure of hydroplane boat and stub-wings is a correlated whole. A footing 43 is carried by the interior flooring 22 for suitable anchorage of a forward wing beam brace 43, which centrally braces said beam directly to the hull bottom.

Exterior bracing is provided for each wing beam, that for the leading beam partaking of a dual nature, being composed of the legs or struts 44 which are combined after the manner of the legs of the letter A, or of an inverted V. The extremities of the forward wing beam are thus braced to the fins which they respectively overhang in a fore and aft manner which completes the union between the aerial supporting surfaces and the water supporting surfaces of the flying boat. If desired, the feet of the struts 44 of each A-brace may be connected by a board 44^a, as is best shown in Fig. 1 thus forming a "delta" brace, although the struts 44 are responsible for the main bracing function. Strut diagonals 45 connect each outer extremity of the rear wing beam 35 transversely back to the lower portion of the corresponding hull side 11.

Water-tight bulkheads 46 employ the respective wing beams 34 and 35 as cap stringers for the purpose of subdividing the main cockpit 31 into three separate compartments, there being no communication between any two adjacent compartments for any water which has managed to leak into one compartment. As thus divided, the forward seat 32 becomes available for the

accommodation of passengers, while the rear seat 33 is suitable for the location of the flight controls for the operation of the pilot. The intermediate cockpit compartment is adapted to contain such supplies as the motor fuel, this compartment being capable of carrying a relatively large weight owing to the fact that the trussed wing beams define its limit in a structurally strong manner which is heightened by the fact that the step 14 acts as an intermediate transverse support.

Moreover, since the respective wing beams 34 and 35 are positioned in respectively fore and aft relations to this planing step it will be obvious that the center of lift and the center of gravity will be approximately vertically aligned as the latter is located by the design immediately abaft the step. This will permit of the transportation of a much greater quantity of fuel for the motors than has hitherto been possible and will result in a marked extension of the cruising radius for a flying boat of this type. Moreover, the location of the supplies between the other two cockpit compartments gives the occupants of either the fore or aft compartment ready access thereto. A hatch cover 47 is provided to slide over that part of the cockpit 31 through which the stub-wings 37 extend, in order to protect the supplies from inclement weather and the like. The stub-wings are surfaced to provide sidewalks whereby the occupants of either of the cockpit compartments will be given an advantageous location for the inspection of the motors which in my type of flying boat, such as here disclosed, are supported by a composite wing post structure erected over the boat.

It should now be apparent that the objects previously presented have been attained by the constructions described in the foregoing so that it now remains but to point out that one specific embodiment only of the invention has been described and illustrated, and to emphasize the fact that other adaptations of this invention may be made in accordance with the variance of conditions concurrent with their adoption, in any manner within the scope and definition of the appended claims.

What is claimed is:

1. In a hull for flying boats, a hydroplaning bottom, and fin excrescences formed by extending the bottom planking laterally beyond the chines of the boat body proper.
2. In a hull for flying boats, a hydroplaning bottom, and fin excrescences formed on the boat body proper by extending the bottom planking continuously and uninterrupted from the longitudinal center of said bottom laterally to the margins thereof.
3. In a hull for flying boats, a hydroplaning bottom, fin excrescences arranged to

- augment the hydroplaning area, and a base for the fin bottoms formed by extending portions of the interior framework of the boat body proper laterally beyond the 5 chines.
4. In a hull for flying boats, planking arranged to provide a hydroplaning bottom terminating in a rearwardly facing step, fin surfaces provided by an extension or said 10 planking in alignment with said bottom and terminating squarely in alignment with said step.
5. In a hull for flying boats, a cockpit provided in the hull, wing supports arranged intermediately across the hull to intersect the cockpit, and bulkheads disposed in the vertical plane of the respective supports to subdivide the cockpit into adjoining 15 cockpit compartments.
6. In a hull for flying boats, wing supports arranged intermediately across the hull, a cockpit provided in the hull to extend both fore and aft of the wing supports, bulkheads disposed in the vertical 20 plane of the respective supports to subdivide the cockpit into adjoining compartments, and a center covering for the intermediate compartment.
7. In a hull for flying boats, a cockpit provided in the hull, wing supports arranged intermediately across the hull to intersect the cockpit, and braces for each wing support extending both fore and aft.
8. In a hull for flying boats, fore and aft 25 cockpit compartments, a wing structure built into the boat between the compartments and bulkheads associated with said wing structure.
9. In a hull for flying boats, an elongated 30 cockpit, a wing structure built into the boat intermediately of the cockpit, and bulkheads associated with said structure for subdividing said cockpit.
10. In a hull for flying boats, an elongated 35 cockpit, wing beams extending transversely of the hull intermediately of the cockpit, and a bulkhead associated with each wing beam to subdivide said cockpit.
11. In a hull for flying boats, a planing 40 bottom terminating in a step, an elongated cockpit arranged in said hull, and a wing structure built into said hull immediately over said step and centrally of said cockpit.
12. In a hull for flying boats, a planing 45 bottom terminating in a step, wing beams transversely built into said hull fore and aft of said step, and bulkheads arranged with said beams to provide water-tight compartments fore and aft of said step.
13. In a hull for flying boats, fins projecting laterally from the hull bottom, wings 50 projecting laterally from the hull top, and braces between the outer ends of the wings and respective fins.
14. In a hull for flying boats, a hydro- 55 planing bottom laterally extended to provide auxiliary planing surfaces, wings built into the hull to longitudinally and transversely overlap said fins, and braces from each fin to a common intersection upon the 60 respective wings.
15. In a hull for flying boats, a hydroplaning bottom laterally extended to provide auxiliary planing surfaces, wings projecting from the sides of said hull over said 65 surfaces, braces arranged between said wings and said surfaces, and braces from said wings to said hull.
16. In a hull for flying boats, a planing 70 bottom terminating in a step, a cockpit provided in said hull, wing beams built into said hull fore and aft of said step and a bulkhead associated with each wing beam to subdivide said cockpit into passenger 75 compartments fore and aft of said step, and a storage compartment immediately over said step.
17. In a hull for flying boats, a hydroplaning bottom extending from the nose of the boat to a rearward termination at a 80 transverse step formed in said hull, a deck, a diminishing tail portion joining said deck and said bottom, an elongated cockpit provided in said deck and defined by a continuous 85 combing, and stub-wings built through said hull intermediately of said cockpit.
18. In a hull for flying boats, a planing 90 bottom terminating in a step, a cockpit provided in said hull, wing beams built into the hull fore and aft of said step, bulkheads 95 arranged with respective wing beams to subdivide said cockpit into passenger, storage and pilot compartments, and bracing means for said wing beams respectively connecting to said step and extending into said passenger and pilot compartments.
19. In a hull for flying boats, a cockpit 100 provided in the hull, wing supports arranged intermediately across the hull to intersect the cockpit, a planing step formed in the hull bottom intermediately of the 105 wing supports, and means tying and bracing each wing support to said step.
20. In a hull for flying boats, a hydroplaning bottom, a deck extended at one end aft beyond said bottom, a cockpit provided in the hull to extend well forward above and well aft beyond said bottom, and means subdividing the cockpit to provide an intermediate compartment for the storage of supplies and fore and aft compartments for occupancy respectively by passengers and pilot.
21. In a hull for flying boats, a hydroplaning bottom terminating aft in a rearwardly facing step, a deck extended at one end aft beyond said bottom, a cockpit provided in the hull to extend well forward above and well aft beyond said bottom, wing 125

supports arranged intermediately across the hull respectively in advance of and aft of said step to intersect the cockpit, and means subdividing the cockpit in separate compartments in the plane of the wing supports.

22. In a hull for flying boats, lateral fin

excrescences formed on the hull adjacent its bottom, wings extending intermediately across the hull above said fins, and braces 10 between said wings and the fins respectively.

In testimony whereof I affix my signature.

GLENN H. CURTISS.
